F. N. Barber

UNITED STATES PATENT OFFICE.

REUBEN H. OBER, OF GARRETTSVILLE, OHIO.

FILING BOX OR DRAWER.

No. 809,976.

Specification of Letters Patent.

Patented Jan. 16, 1906.

Application filed June 9, 1903. Serial No. 160,697.

To all whom it may concern:

Be it known that I, REUBEN H. OBER, a citizen of the United States, and a resident of Garrettsville, in the county of Portage and State of Ohio, have invented or discovered new and useful Improvements in Filing Boxes or Drawers, of which the following is a specification.

My invention relates to filing boxes or drawers which may be entered into and withdrawn from the pockets or holes of filing cabinets.

It is the object of my invention to make a filing box or drawer which will not bind on the sides of the pockets, which may be adjusted to various lengths, which may be suspended on the cabinet when fully withdrawn from its pocket, and which may have its parts quickly, easily, and cheaply constructed integrally with its finger-pull and label-holder.

Other objects of my invention will appear hereinafter in the detailed description thereof.

In the drawings which form a part of this specification, Figure I is a perspective of my invention with the rear portion thereof broken away; Fig. II, a plan of a fragment of a sheet from which the front of my filing box or drawer is made, showing the lines on which the sheet is cut and folded to form the finger-pull and label rest or holder; Fig. III, a fragment of a cabinet in vertical section through a series of pockets, together with the rear portion of a filing box or drawer, all illustrative of the manner in which the box or drawer is held when withdrawn from its individual pocket; Fig. IV, a plan of a fragment of a filing box or drawer, showing an adjustable means for supporting the forward or lower end of the articles in the box or drawer; and Fig. V, a vertical section of a fragment of the front of the box or drawer, showing a second form which the label rest or holder may assume.

I designate my filing box or drawer, having the parallel sides 2, the flat bottom 3, the front 4, the back 5, and the top 6. The lower portions of the sides 2 are flared outwardly or provided with integral lateral longitudinal ribs, extensions, or projections 7 at the junction of the sides with the bottom or at other selected places for the purpose of reducing the friction and the liability of binding by any slight changes in the width of the sides due to the pressure of the filed articles or otherwise. The projections are the only portions of the

filings-box that frictionally engage with the sides 12 of the filing-cabinet, the other parts of the box being spaced therefrom slightly. The rear upper part of the sides 2 are cut off 60 on inclines 8, as shown in Figs. I and III, and between the reduced rear ends of the sides is secured the back 5, which reaches nearly to the top edges of the sides and may extend entirely to the top thereof, if desired. To the 65 rear side of the back is secured by riveting, soldering, or otherwise a strip of metal 9, having a hook 10, with its open mouth toward the front and partially or wholly below the bottom 3. The filing-box slides on the top 70 of the guides 11 on the sides 12 (one only being shown) of the cabinet. The hook 10 rides just above the bottoms 13 of the pockets, which are placed a little below the tops of the said guides 11 to provide a way for the 75 hook 10. This arrangement of the hook and the guide and the pocket-bottoms may be varied, however.

Below the top of the guides and near the front of each pocket is a rod 14 in the path of 80 the hook 10, so that when the box is withdrawn the hook engages the rod. The box may then be swung down into the position shown in Fig. III, the hook holding the box suspended in a position from which papers 85 may be taken or into which they may be placed and where the box is by merely raising its lower end ready to be returned to its pocket.

The top 6 may cover as much of the top of 90 the box as desired; but I have shown it over only the forward portion thereof, where it serves to keep the contents of the box in place, especially when the box has been swung down, as in Fig. III, or the box is full. 95

I may make the sides of the box or drawer corrugated, as shown at 15 in Fig. IV, or the corrugations may be on strips secured to the sides of the box or drawer. Into opposite corrugations 15, which are really guides, I slide a gate or stop 16 for the front end of the filed articles, so that articles of different lengths can be accommodated in the various boxes in the cabinet used. The gate or stop 16 also serves to divide the box into compartments for different articles. The rib 7 may be used with the corrugated sides, if desired.

The box is closed by the front 4, extending beyond the box members, to which it is attached in any convenient manner. In this front I provide a label rest or holder 17, which

is integral with the front 4 and is made by making a cut on three sides of a rectangle and bending back the cut portion on the lower uncut side of the rectangle. The three 5 cuts of the rectangle are shown by the numerals 18, 19, and 20 on Fig. II and the place of bending by the dotted line 21. An arched cut 22 is made within the rectangle, the base of the arched cut being on the dotted line or 10 near that line. That part of the rectangle left at the sides of and above the arched cut is bent back beyond the inner side of the front 4, as shown in Fig. I, where the bottom of the label-rest is inclined, or in Fig. V, where 15 the label-rest is shown as a pronounced shoulder, (marked 23.) The tongued or rounding part 24 of the rectangle left within the arched cut is bent forward on the dotted line 21 to form a curved handle or finger-pull 20 25, by which the box or drawer may be lifted on the hook 10 or pulled out of its pocket. The bending of the finger-pull 25 forward leaves the opening 26, and the bending back of the label-rest leaves an opening through 25 which the label is read.

The label showing the contents of the box is slipped in between the body of the front 4 and the rest 17 and is supported on the portion of the rest 17 which connects it with the 30 front 4. The label may be inserted from behind the top 6, as is clear, or through the

opening 27 in the forward end of one of the sides 2, or said opening may be at the forward end of the top 6.

While I have given the particular shape of 35 the various cuts which are made in the sheet from which I make the front 4, it is to be understood that cuts of various other shapes may be made.

Having described my invention, what I 40 claim is—

1. In a filing box or drawer front, a handle and label-holder integral with the front, the former being a portion of the front bent outside the box and the latter a portion thereof 45 bent within the box.

2. In a filing box or drawer front, a label-holder and a handle integral with the front and consisting of portions bent in opposite directions from the body thereof, the portion 50 containing the opening from which the handle is bent being bent to form a label-holder.

3. In a box or drawer, a front having a handle integral therewith and a label-holder integral therewith and formed of a single 55 tongue extending each side of the handle.

In witness whereof I hereunto subscribe my name this 5th day of June, 1903.

REUBEN H. OBER..

In presence of—

R. S. WEBB,

W. E. AGLER.
